UNITED STATES PATENT OFFICE

123,686

DESIGN FOR A KEYBOARD FOR ELECTRICAL MUSICAL INSTRUMENTS

George H. Stephens, Glencoe, Ill., assignor to
Hammond Instrument Company, Chicago, Ill.,
a corporation of Delaware

Application June 3, 1940, Serial No. 92,794

Term of patent 14 years

To all whom it may concern:

Be it known that I, George H. Stephens, a citizen of the United States, residing at Glencoe, in the county of Cook and State of Illinois, have invented a new, original, and ornamental Design for a Keyboard for Electrical Musical Instruments, of which the following is a specification, reference being had to the accompanying drawing, forming part thereof.

Figure 1 is a perspective view of a keyboard for electrical musical instruments showing my design; and

Figure 2 is a top plan view thereof.

I claim:

The ornamental design for a keyboard for electrical musical instruments, as shown.

GEORGE H. STEPHENS.
